UNITED STATES PATENT OFFICE.

BYRD C. ROCKWELL, OF CAMDEN, ARKANSAS.

COMPOSITE LUMBER.

Application filed April 9, 1921. Serial No. 460,059.

To all whom it may concern:

Be it known that I, BYRD C. ROCKWELL, a citizen of the United States, residing at Camden, Ouachita County, Arkansas, have 5 invented a certain new and useful Improvement in Composite Lumber, of which the following is a full, clear, and exact description, such as will enable others skilled in the art to which it appertains to make and 10 use the same, reference being had to the accompanying drawings, forming part of this application, in which—

Figure 1 and Figure 2 are detail views of one form of my invention; and, 15 Figure 3 is a cross sectional view of another form thereof.

This invention relates to a new and useful improvement in composite lumber. Heretofore, in joining two or more pieces of wood, 20 the adhesive was applied to the entire surfaces of the contiguous faces so that the adhesive was present on the joined faces of the pieces glued together. The presence of this adhesive on the faces of the composite 25 lumber causes the discoloration or staining of the wood by the adhesive and renders the glue line conspicuous, particularly with many kinds of hardwoods. Furthermore, such glue lines come in contact with the 30 machine knives or cutters and quickly destroy the cutting edge of the tool, and unless the tool is frequently sharpened, the contour of the article is destroyed by the uneven edge of the tool.

35 The objects of this invention are: To eliminate the glue lines from the face or faces of the composite lumber so that the joint will not become prominent by the presence of adhesive or by the staining or discoloration of the face of the lumber by the glue; and the cutting edges of the tools used in cutting or finishing operations are not broken or dulled by coming in contact with the glue. The composite lumber produced 40 according to my invention is free from the glue lines on its joined faces so that the joint is not rendered conspicuous and the staining or discoloration of the joined faces by the adhesive is prevented, thereby enhancing the appearance of the article.

In the drawings, 1 and 2 represent sections whose contiguous sides are formed with relatively small matching tongues 3 and grooves 4 (preferably arranged to one side of the center line). To one side of these tongues and grooves, on one of said contiguous

sides, is applied an adhesive (such as glue), as indicated at 5, and the sides are clamped together in close contact while said glue is setting. The tongue (or groove, 60 depending on which side the glue is applied) defines the marginal edge of the glue line and prevents the glue from spreading and overflowing into the space on the other side of the tongue (or groove) 65 thus insuring a free-faced article, i. e., an article having one face, say the upper, whose contiguous joined edges are free from glue.

To make a double free-faced article, I 70 may employ two tongues 3' and 4', as shown in Figure 3, each tongue (or groove) defining the marginal edge of the adhesive, indicated at 5', and preventing its overflow. In this instance, the adhesive is confined to 75 the center line between the contiguous sides, and both faces of the article can be planed or worked without danger of contact with the glue.

The restriction of the marginal edge of 80 the adhesive within a definite distance from the faces of the joined articles leaves said faces free so that they can be worked without injury to the tools from coming in contact with the glue.

My improved composite lumber can be 85 easily manufactured and advantageously used wherever a joined face free from adhesive is desired.

What I claim is:

1. Composite lumber consisting of two 90 members, an adhesive substance applied to the contiguous sides of said members and securing them together, and means for confining one of the marginal edges of said adhesive substance so as to leave a clear unglued face on one side of said composite lumber. 95

2. As a new article of manufacture, composite lumber consisting of two members, an adhesive substance applied to the contiguous sides of said members, and means for restricting the marginal edges of said adhesive substance within a definite distance from the faces of said composite lumber so as to leave said faces free from said adhesive substance. 100 105

3. Composite lumber consisting of two members, an adhesive substance applied to one of said members for securing together the contiguous sides of said members, and cooperative means formed on the contiguous sides of said members for confining the mar- 110

ginal edge of said adhesive substance a pre-determined distance from one of the joint faces of said members.

4. Composite lumber consisting of two members, an adhesive substance applied to the contiguous sides of and securing together said members, there being a tongue formed on the contiguous sides of one of

said members, and a groove formed on the contiguous side of the other one of said members and adapted to receive said tongue thereby preventing the adhesive substance from reaching one joint face of said lumber. 10

In testimony whereof I hereunto affix my signature this 5 day of April, 1921.

BYRD C. ROCKWELL.
